UNITED STATES PATENT OFFICE.

MARTIN FEEDERS, OF MASURY STATION, OHIO.

FLYING-MACHINE.

1,344,297.

Specification of Letters Patent. Patented June 22, 1920.

Application filed April 13, 1920. Serial No. 373,535.

To all whom it may concern:

Be it known that I, MARTIN FEEDERS, citizen of the United States of America, residing at Masury Station, in the county of 5 Trumbull and State of Ohio, have invented certain new and useful Improvements in Flying-Machines, of which the following is a specification.

This invention relates to air craft. The 10 principal object is to device a machine provided with a regular propeller and in addition to this, two propellers energized by independent means. One of the independent propellers is located on the top and near 15 the front end of machine. The second independent propeller is located at the rear of the machine.

Another object is to provide means for moving the front independent propeller 20 along a segmental rail, thereby giving the propeller shaft a perpendicular position or approximately any angle between the perpendicular and 45°.

A still further object is to provide means 25 for tilting the rear independent propeller, and also to cause it to move along a segmental rail when in a vertical or lateral position, or any degree within the tilting mean or extremes of the segmental rail.

30 The drawing illustrates a preferred embodiment of the invention. However, it is to be understood that in adapting the same to meeting different conditions, various changes in the form, and minor details of 35 construction may be resorted to without departing from the nature of the invention as claimed and set forth in the drawings:

Figure 1 is a side elevation.

Fig. 2 is a top plan view.

40 Fig. 3 is a detail view partly in section.

Fig. 4 is a detail view partly in section.

Fig. 5 is a sectional view taken on line A—A of Fig. 3.

45 Corresponding and like parts are referred to in the following description and indicated in the several views of the drawings by like reference characters.

By referring to Figs. 1 and 2 it will be seen that the machine embodies a hull or 50 shell 1 which comprises a forward cylindrical portion 2 and a rear tapering portion 3. A bracket 4 is secured to the underside of the forward portion 2 and is provided with a rolling support 5. A trailing skid 6 is 55 secured to the underside of the tapering 3, and acts jointly with the rolling support 5,

to sustain the machine when traveling upon a surface as when alighting or taking off.

For proper steering, the machine is provided with rear rudders 7 and 8, the rudder 60 7 occupying a vertical position, and the rudder 8 being horizontally disposed. These rudders may be of any conventional type and adapted to be manipulated by suitable operating means.

65 A cockpit 9 is located about medially of the hull or shell 1 and is designed with view to assemble the operating levers of the various parts to be actuated.

70 For sustaining the machine during flight it is provided with laterally extending planes 10 which may be of conventional construction.

The machine is equipped with a conventional type of engine and designated as engine 11, which energizes the propeller 12.

75 The lifting and propelling blade 13 is energized by means of an electric motor 14, which in turn secures its current for energizing same from a generator 15 which is 80 in turn energized by an independent motor 16.

85 In order to move the shaft 18 along the segmental rail 17, I have provided a hydraulic motor 19 (see Figs. 3, 4 and 5). This motor 19 is secured to the shaft 18. 90 This motor consists of two fluid gears 20 secured within a housing, one of said fluid gears 20 being provided with an extended shaft end 21 carrying a cog wheel 22 registering with the teeth on the segmental rail 17.

95 By referring to Fig. 5 it will be seen that the housing containing the fluid gears 19 has intakes or outlets 23 connected with a pump 24, as indicated in Fig. 1. The connection may be of a pliable hose type or of any other suitable construction.

100 At the rear end of the machine I have provided a bracket 25 secured to the body of machine. Firmly secured to this bracket 25 is a rod 26. At the outer ends of this rod 26 the ends of a segmental rail 27 are firmly secured. A shaft 28 carrying an electric motor 29 similar to motor 14 energizes a blade 30. In order to move the shaft 28 105 along the segmental rail 27, I have provided a hydraulic motor 31 similar in every way with the motor 19 above described.

110 When it is desired to use the blade 30 for lifting, I have provided an arm 34 to the bracket 25 which is coupled to a hydraulic cylinder 32 by means of a link 33. This

hydraulic cylinder 32 is provided with a piston 35, which is caused to act by means of a fluid pressure exerted as desired upon either side of a piston head of ordinary construction. The piston 35 is caused to move in or out, thereby tilting the segmental rail 27 and connected parts by pressure exerted by means of the pump 24 suitably connected to the cylinder 32.

10 It is apparent that by means of the tilt and side motion of the rear lift and propeller blade 30 the machine can be set so that if unbalanced, due to a broken end of plane, or side strain due to any cause the machine, 15 can be sustained in an upright position. Further that when the primary motor for any reason will not work, the secondary motor may be employed. Again when desired

to start from a limited surface, the front blade 13 and the rear blade 30 may be positioned for a direct upward pull. 20

What I claim as new is:

A device of the class described comprising an adjustably mounted propeller shaft and means for adjusting the same, including a 25 hydraulic motor mounted on the shaft, a motor pressure pump connected with the motor and an electric generator for energizing the pump motor, substantially as described.

30 In testimony whereof I affix my signature.

MARTIN FEEDERS.
